UNITED STATES PATENT OFFICE.

LAFAYETTE LEVINGSTON, OF SAN FRANCISCO, CALIFORNIA.

BOTTLE-STOPPER.

1,178,451.

Specification of Letters Patent.

Patented Apr. 4, 1916.

Application filed December 22, 1913. Serial No. 808,068

To all whom it may concern:

Be it known that I, LAFAYETTE LEVINGSTON, residing in the city and county of San Francisco, State of California, have invented certain new and useful Improvements in Bottle-Stoppers, whereof the following is a specification.

This invention relates to closures especially for milk bottles, and more especially to that class which consists in a more or less flexible disk that engages a croze in the bottle and is thereby retained in place. As is well known these closures have to be removed to get out the contents of the bottle. 10 This is done either by a tag stapled onto the disk which tag necessitates the disk being applied with the tag side up; or else, in the case of a plain disk, a tool is required. By my invention I avoid both these objectionable features. This I do by incompletely cutting out a portion of the disk, which portion may be opened by a pressure of a finger or instrument, thus forming an opening or hatchway in the disk, through which the 20 contents of the bottle may be discharged, or a finger inserted to raise the disk and remove it completely.

In the accompanying one sheet of drawing I have illustrated my invention by representing an embodiment of it in its best form.

In the drawings: Figure 1, is a sectional elevation of a milk bottle with my disk in place and the hatchway open after the closure has been pressed down. Fig. 2, is a perspective view of a disk with the hatchway open. Fig. 3, is a plan of a disk with the hatchway closed, and, Fig. 4, is a section on the line 4, 4 of Fig. 3.

In these figures: 1 represents a milk bottle of the usual form, provided with the usual croze 2, to engage and hold a disk 3, said disk being commonly made of a heavy paper or card board. The disk 3 is provided with a hatchway 4 of approximate square shape, formed by cutting through the material or nearly so along the line 5, 5. The cut does not completely encircle the hatchway, but leaves a portion of its periphery or circumference intact to form holding means, as at 6, 6 whereby the hatch 7, is retained in place either in a closed or opened position.

In practice I have found it convenient to make the cuts 5, 5 with a knife die, either before or after cutting out the disk, and

then the device may be treated with paraffin whereby the cuts 5, 5 are sealed and the disk made impervious and sterile.

When the disk is in place in the bottle, the hatchway remains closed. To open the same it suffices to press with a finger or instrument upon the hatch 7, at either of the cut sides, as at 8 and depress that side, whereby the opposite side may be raised, the whole hatch tilting at the intact portions, as shown in Figs. 1 and 2. The contents of the bottle may be poured out through one of the corners of the open hatchway, or a finger may be inserted and the whole disk lifted away from the bottle.

Having thus described my invention and believing I have produced useful and novel improvements in the art to which it appertains, let it be understood that I do not wish to be limited to the exact arrangement of the several parts composing the same as many changes can be made without departing from the spirit thereof, but

What I claim and desire to secure by United States Letters Patent is:

1. A bottle closure comprising a disk provided with a central square hatchway and a hatch closing the same formed by cutting through the disk a portion of the sides of two opposite corners and the remaining integral corners forming holding means to keep said hatch in position.

2. A bottle closure comprising a disk provided with a hatchway of approximate square shape, a hatch in said hatchway formed by cutting through the disk around a portion of the periphery of the hatchway and the remaining integral portion adapted to form central means to keep said hatch in position.

3. A bottle closure comprising a disk provided with a hatchway of approximate square shape closed by a correspondingly shaped hatch formed by cutting through the disk except at two opposite corners of the hatch, said corners being adapted to retain the hatch centrally in an opened position within the hatchway.

In testimony that I claim the foregoing I have hereto set my hand in the presence of 105 witnesses, the 28th day of November, 1913.

LAFAYETTE LEVINGSTON.

Witnesses:

J. H. THELLER,
C. ROSENTHAL.
